NECKTIE WRAPPER

Harry A. Berger, New York, N. Y.

Application June 28, 1934, Serial No. 732,945

2 Claims. (Cl. 206—78)

This invention relates to a new and useful improvement in a necktie wrapper and has for an object to provide an improved necktie wrapper whereby a plurality of neckties may be packed securely in such a manner to prevent the same from slipping within the package and to prevent creasing and soiling of the neckties in handling and shipping.

Yet a further object of this invention is to provide a necktie wrapper formed of a section of card board and a section of paper, wherein the card board forms a stiffening or backing support for the tie to hold the same flat against creasing, and wherein the paper is folded thereto about to hold it in such position, yet permitting a portion of the tie pattern of the top tie to be visible.

Yet a further object of this invention is to provide a necktie wrapper formed of a combination of card board and paper, wherein a minimum portion of the paper receives adhesive to seal the package so that the package may be sealed and thereafter opened with a minimum of effort.

At present manufacturers of men's neckwear have no secure or satisfactory way of wrapping neckwear in a bulk for shipping the same to their customers at distant points and many complaints are received by neckwear manufacturers from their customers that the shipments are received with the ties loose and creased in the packages.

The present method of packing neckwear is to fold them the long way in half and place six ties on top of each other and place a paper gummed end band around the six ties at the narrow end and likewise a paper band at about five inches above the bottom wide end. Then many bundles of six ties each are placed into a carton and so shipped to customers. The ties being mostly made of silk, a slippery fabric, do not stay within the paper bands but slip out. The ties also drop down to the bottom of the container no matter which side they are placed. They stay in the position as they are originally packed only if the box is left flat and not handled.

Another method of present necktie packing is the same as mentioned above, but with a tapered card board cut to the shape of the ties and the paper bands placed around the ties and the card board, then packed the same way in cartons. This method is somewhat better than the first mentioned, but the same trouble exists, the neckties slip out from under the paper band and the ties drop to the bottom of the

container causing them to crease and wrinkle. Some manufacturers slip the bundle of six ties into a tapered glassine bag or envelope. This is an improvement over the first and second method, but the same condition exists, if the bag is loose enough to insert the ties, then they will drop to the bottom when the carton is handled in transit. If the bag is tight enough to hold them in position, then they cannot be inserted without wasting lots of time or tearing the bag.

With the foregoing and other objects in view, as will hereinafter become apparent, this invention comprises the constructions, combinations and arrangements of parts hereinafter set forth, disclosed, and shown on the accompanying drawing. In this drawing,

Figure 1 is a perspective view of the invention in sealed position.

Figure 2 is a perspective view of the invention in open position, the ties being represented by the broken lines.

Figure 3 is a sectional view taken on the line 3—3 of Figure 1, and

Figure 4 is a sectional view taken on the line 4—4 of Figure 1.

There is shown at 10 the completed neckwear or necktie containing package ready for shipment. As shown in Figure 2, this package 10 is made up of a card board 11 shaped to substantially conform to the outline of the ties 12 which are to be placed thereon. Secured along one edge of the card board 11 as at 13 is a paper sheet consisting of a fold 14, a second fold 15, and a triangular flap 16 provided with a suitable adhesive 17 along one edge thereof. The first fold 15 is provided at each end with a pair of flaps 18 and 19 adapted to be tucked in to the ends of the package 10 and prevent dust from entering therein.

As will be observed, the card board 11 and the folds of the wrapper 14 and 15 are each tapered in outline conforming to the tapering shape of a tie 12 in folded position. The first fold 14 is connected to the securing edge 13 by a slightly tapered hinging portion 20 and similarly a slightly tapered hinging portion 21 connects the fold 14 to the second fold 15, it being observed from the completed package 10 that the hinging portions 20 and 21 taper in a direction opposite to the taper of the support 11 and the folds 14 and 15 for the package 10 adjacent the end 24 of the ties is thick and narrow, while the other end of the package 10 adjacent the end 25 of the ties is wide and shallow.

The fold 14 may be provided with a glassine, cellophane or other transparent flexible window 22 beneath an opening 23 enabling the pattern of the top tie 12 to be visible therethrough.

5 In operation, this package 10 is generally used for packing and shipping a half a dozen ties 12 generally all of the same pattern from the manufacturer to the retailer and serves the purpose of keeping the ties in the same condition as which they are packed by the manufacturer. The six ties 12 are laid folded in half on the cardboard 11 and the folds 14 and 15 folded thereabout with the adhesive 17 of the sealing flap 16 folded over the first fold 14, the end flaps 18 and 19 being tucked therein during the process. When the ties 12 are folded over as shown, the folded ends 24 are much thicker than the loose ends 25 and the shape of the package 10 conforms to this variation in thickness of the folded ties.

10 The ties are thus secured in their full length in folded position and they cannot slip in any direction. They cannot slip from the folded end 24 towards the loose end 25 because the bulk at the end 24 is greater than at the end 25 and becomes gradually smaller as it approaches the end 25. They cannot slip from the end 25 towards the end 24 because the taper is wider at end 25 and gradually becomes narrower. The ties 12 are thus held immovable and safe in the sealed package 10 during shipment even though the package may be turned end for end or placed in any direction. Inasmuch as ties when sold in wholesale lots generally include at least one-half dozen of the same pattern it is only necessary to see the top tie in order to know the pattern of the ties in the package 10.

15 Once the package is received by the retailer, he will open the package and display the ties in his windows or show cases in the customary manner, this package being intended and serving solely for the purpose of transporting ties in quantities from the manufacturer to the re-

tailer. Ties are generally silky in finish and hence slippery and prior to this invention there is no known way of so shipping ties as to prevent their gathering in one end or the other of the shipping package and hence unsaleable. 5

20 The novel features and the operation of this device will be apparent from the foregoing description. While the device has been shown and the structure described in detail, it is obvious that this is not to be considered limited to the exact form disclosed, and that changes may be made therein within the scope of what is claimed without departing from the spirit of the invention.

25 Having thus set forth and disclosed the nature of this invention, what is claimed is:

1. A packaging means for a plurality of neckties comprising a tapered stiff supporting member corresponding in taper to the taper of a plurality of neckties folded in half and placed 20 thereover, and a wrapping member adapted to be secured about said supporting member and said ties, the folds of said wrapping member tapering correspondingly to the taper of said supporting member, and the hinged portions of 25 said folds tapering in reverse direction to the taper of the folds.

2. A packaging means for a plurality of neckties comprising a tapered stiff supporting member corresponding in taper to the taper of a 30 plurality of neckties folded in half and placed thereover, a wrapping member adapted to be secured about said supporting member and said ties, the folds of said wrapping member tapering correspondingly to the taper of said supporting member, the hinged portions of said folds tapering in reverse direction to the taper of the folds, and a transparent window in one of 35 said folds permitting the pattern of the uppermost enclosed tie to be visible.

40 HARRY A. BERGER.
